UNITED STATES PATENT OFFICE.

CHARLES W. KIRSCH, OF STURGIS, MICHIGAN, ASSIGNOR TO KIRSCH MANUFACTURING CO., OF STURGIS, MICHIGAN, A CORPORATION OF MICHIGAN.

CURTAIN-ROD.

1,240,582.

Specification of Letters Patent. Patented Sept. 18, 1917.

Application filed July 24, 1916. Serial No. 111,009.

To all whom it may concern:

Be it known that I, CHARLES W. KIRSCH, citizen of the United States, residing at Sturgis, in the county of St. Joseph and State of Michigan, have invented certain new and useful Improvements in Curtain-Rods; and I do hereby declare the following to be a full, clear, and exact description of the invention, such as will enable others skilled in the art to which it appertains to make and use the same.

My invention relates to improvements in curtain rods, the object being to provide a sectional rod, the parts of which shall be adapted for association in various relations to produce rods of greatly varying length.

A further object of my invention is to provide a system by means of which a dealer in curtain rods shall be able to provide rods of any length desired, without necessity of cutting, and by the use of a minimum number of parts of differing shapes or dimensions.

A further object of my invention is to provide a sectional curtain rod having several telescopically interfitting parts and adapted to be locked at the several joints by means of wedging or locking devices of uniform dimensions.

A further object of my invention is to provide simple coupling means for a two-piece telescopically adjustable curtain rod by means of which the rod can be lengthened beyond its normal length.

My invention consists in a curtain rod having two end members which are adapted to be telescopically connected together, a coupling member adapted to telescopically receive each of the end members, and means for locking the coupling member to the end members.

My invention also consists in a tubular coupling member for curtain rods in combination with longitudinal members of similar cross-section which are adapted to be telescopically joined, the coupling member being adapted to be interposed between the other members and formed for telescopic connection with each and the several telescopic joints being adapted to be locked by locking devices of uniform dimensions.

My invention also consists in the several combinations and arrangements of structures and parts and in the features of construction by means of which I am enabled to at-

tain the above and other objects, all as hereinafter described and claimed.

My invention will be more readily understood by reference to the accompanying drawings forming part of this specification, and in which:

Fig. —1— is a perspective view of a curtain rod formed in accordance with my invention.

Fig. —2— is a perspective view of a two-piece extension rod.

Fig. —3— is a fragmentary rear elevation of the rod showing one means of locking the several joints.

Fig. —4— is a fragmentary horizontal section on the line 4—4 of Fig. —3—.

Fig. —5— is a detail vertical section on the line 5—5 of Fig. —3—.

Fig. —6— is a view similar to Fig. —3— showing another means of locking the several telescopic joints.

Fig. —7— is a horizontal section on the line 7—7 of Fig. —6—.

Fig. —8— is a fragmentary front elevation of a rod built up of a number of the coupling members.

In the modern development of manufacturing and marketing devices of this character, much has been accomplished in the way of reducing the manufacturing operations to a minimum, reducing the possible waste of material, and in the simplification of operations and methods of producing articles of the different dimensions required which shall require a minimum stock to be carried by the dealer.

In the curtain rod business, the usual variations in lengths required are from twenty-five inches to forty inches, and two-piece telescopically extensible rods are produced which may be termed the standard or stock size suitable to fill such demands. It goes without question that if such rods are made in very large quantities the manufacturing cost can be reduced. My system contemplates the use of such standard length rods which constitute the vast majority of rods used, as a base, and by means of such standard rods, and my improved couplers, which can be made of uniform length or of different lengths, as desired, producing rods of any greater length which may be called for or needed.

Ordinarily I prefer to make use of stand-

ard length couplers, and by the use of one or more in combination with a standard length rod produce a rod of any length desired, but it should be understood that by 5 means of different length couplers used with rods of shorter than the desired length, the dealer can produce any length of rod called for.

As illustrated in the drawings my improved sectional rod comprises two formed 10 end members A and B. In section, as shown in Fig. —5—, these members are each channel shape having inturned overlapping flanges C, and the various sections of the 15 rod are formed for interfitting telescopic engagement. The outer ends D of the two sections may be formed in any suitable manner for hanging or supporting the rod for instance like that shown wherein the ends 20 D are bent at right angles to the bodies of the end members and are adapted to be hung on suitable supporting brackets E.

I usually make the body portions F and 25 G of the end members to constitute these two members a curtain rod capable of being extended to forty inches or to that length which constitutes the longer length of the most usual sizes, the two ends F and G being formed for telescopic engagement 30 with each other as shown in Fig. —2—, that is, the end F telescopically fits within the end G.

For building up rods longer than the 35 standard or ordinary length, I provide telescopic couplers H, one end J of which is of dimensions to telescopically fit over the connecting end F of the smaller end section A and the other end K of which is formed small enough to fit within the connecting end G of the larger end member B. In other words, the large end J of the coupling member is the same size as the end G of the end member B and fits upon the opposite end member A in the same manner, and 45 likewise the small end K of the coupling member is the same size as the connecting end F of the end member A.

As stated hereinbefore I prefer to make the coupling members H of uniform length 50 using any number of them which may be necessary in combination with the standard end members A and B to produce the length of rod desired. Fig. —8— illustrates a rod composed of the end members A and B and 55 a plurality of the coupling members H.

On the other hand, for some purposes, it is advantageous to make the coupling members H of different lengths so that but one thereof shall be necessary in combination 60 with the standard end members A and B for the production of a rod of the desired length, as illustrated in Fig. —1—.

For locking the several telescopic members together in their adjusted positions I 65 may use the oval locking washer L, as illus-

trated, or I may crimp the overlapping edges C of the members, as shown in Figs. —6— and —7—. My method of building up the rods with the couplers provides that the inside members at each joint which receive the locking washers are uniform in cross-section, and consequently the locking washers are uniform in dimensions and are thus most cheaply produced. The washers are of a size in one direction to be easily 70 slipped into the rod into the position desired, and are enough larger on another diameter so that when they are forcibly turned to the positions shown in Fig. —3—, they expand the inner of the telescopic members 80 against the outer one thereof and thus frictionally lock the two against relative longitudinal movement.

In some instances I prefer to crimp the overlying edges of the telescopic members 85 as shown in Figs. —6— and —7—, forming these edges inwardly at the same points to provide interengaging projections M and recesses N which prevent the relative longitudinal movement of the two members. These notches or crimps are relatively small, but I make a sufficient number of them to firmly hold the members against longitudinal displacement. I do not herein claim this crimping method of interlocking the 95 telescopic members, the latter forming the subject-matter of my co-pending application Ser. No. 111,008, filed July 24, 1916.

I claim as my invention:

1. A sectional curtain rod comprising two 100 similar tubular end members, one thereof of a size to be telescopically received within the other, and a coupling member interposed between the two end members fitting telescopically within the larger of said end 105 members at one end and fitting telescopically upon the other end member at its other end, and means for locking the several members against relative longitudinal movement.

2. A sectional curtain rod comprising two similar end members of channel shaped cross-section having inturned edge flanges one thereof adapted to be telescopically received within the other, and a coupling member of similar cross-section adapted at one end to telescopically fit within the larger end member, and at the other end to telescopically fit upon the other member, and means for locking the end members to the 120 coupling member to prevent relative longitudinal movement thereof.

3. A sectional curtain rod comprising two main members adapted for telescopic engagement with each other at their opposed 125 ends, and a coupling member interposed between the opposed ends of said main members and telescopically engaging both thereof, and means for locking the several members against relative longitudinal movement.

4. A sectional curtain rod comprising two end members of channel shape cross-section having inturned edge flanges, and formed for telescopic engagement with each other, a coupling member of similar cross-section interposed between the end members and formed for telescopic engagement of both, and means for frictionally holding the several members against relative longitudinal movement.

5. In a channel-shaped tubular sectional curtain rod having members formed for telescopic interfitting engagement; a coupling member formed at one end for telescopic interfitting engagement with one of said members and at its other end for telescopic interfitting engagement with the other of said members, and means for locking the several members against relative longitudinal movement.

6. A curtain rod comprising two tubular main members, one thereof adapted to telescopically fit within the other thereof whereby the length of said rod may be varied in combination with a similar tubular cou-

pling member adapted to be interposed between the other members and telescopically fitting both thereof and adapted to provide a curtain rod of longer capacity than the extensibility of the two main members, and means for locking the main members to the coupling member to prevent relative longitudinal movement thereof.

7. A sectional curtain rod comprising two similar tubular end members, one thereof of a size to be telescopically received within the other, and a coupling member interposed between the two end members fitting telescopically within the larger of said end members at one end and fitting telescopically upon the other end member at its other end.

In testimony whereof I have signed my name in presence of two subscribing witnesses.

CHARLES W. KIRSCH.
